UNITED STATES PATENT OFFICE.

ETHAN N. HESCOCK, OF WESTFIELD, NEW JERSEY, ASSIGNOR TO NEW JERSEY
FOUNDRY & MACHINE COMPANY, A CORPORATION OF NEW JERSEY.

CONVEYER-SYSTEM CONTROL.

1,375,908.

Specification of Letters Patent. Patented Apr. 26, 1921.

Application filed April 5, 1920. Serial No. 371,504.

To all whom it may concern:

Be it known that I, ETHAN N. HESCOCK, a citizen of the United States, residing in Westfield, in the county of Union and State 5 of New Jersey, have invented certain new and useful Improvements in Conveyer-System Controls, of which the following is a specification.

This invention relates to over-head conveyor systems having electric motor driven hoisting devices thereon, and has for one object to provide means for supplying electric current to the motor without the use of sliding contacts.

Another object of the invention is to provide convenient means for controlling the movement back and forth of the trolley of the conveyer.

Other objects of the invention will appear 20 as the description proceeds; and while herein minute details of the invention are described, the invention is not limited to these, since many and various changes may be made without departing from the scope of 25 the invention as claimed.

In the accompanying drawing, showing by way of example, one of many possible embodiments of the invention,

Figure 1 is a side elevation showing the 30 conveyer system and a row of floor machines from which is derived the operating current for the motor, and to and from which the conveyer may carry material or products; and

Fig. 2 shows a plan of the conveyer system.

My improved conveyer system is shown in combination with a row of separated, electrically driven floor machines, 5, each 40 provided with a socket 6 having its contacts electrically connected to the feed conductors which supply current to the motors of the machines. These machines may be of any kind of electrically driven machines, and 45 while not limited to such as could be conveniently used where an over-head conveyer is needed, will usually be of the kind which require a conveyer system for delivering to the machines material to be worked upon or 50 carrying therefrom a resulting product. However, while the conveyer system is shown in combination with these machines, the invention is not so limited, since a plurality of contact sockets 6, could be spaced along at 55 convenient intervals mounted on suitable

means other than machines, and fed from current other than the feed conductors above mentioned.

The over-head girders 8 of the conveyer system are each suitably supported above or 60 near said machines 5 and are each formed with upper and lower flanges or tracks 9 and 10, between which are received track wheels 11, of a trolley 12 on which are mounted hoisting drums 15 driven by suitable electric motors 17 each provided with a flexible conducting cable 18 provided at its free end with a contact plug 19 adapted to be received in the contact socket 6 of any one of 65 said machines 5 which may be most convenient to the trolley 12 at the time. By this means current is supplied to the motors, without any current carrying sliding contact which would cause dangerous sparking, or without using inconveniently long cables 70 75 18.

Around each drum is wound a hoisting cable 20, and each motor is provided with a convenient operating switch controlled by a pair of flexible controlled devices 21, which 80 may be, for instance, chain, rope, rod or the like, terminating in a ring or other handle.

Means will now be described for driving the trolley 12 back and forth upon the 85 tracks. Mounted upon the end supports 25 of the girder 8 is a platform 26 supporting a standard 27 braced against the support 25 by means of a spacing plate 28. Said standard has rotatably mounted thereon a 90 cable drum 30 connected by means of suitable reducing gears 31 and 32 to the shaft 33 of a cable-drive motor 35 mounted on said platform 26.

A cable 38 connected at opposite ends to 95 said trolley is passed around said cable drum 30, and an idler pulley 39 at the opposite end of the tracks.

Said motor is provided with a suitable control switch diagrammatically indicated 100 at 42 and operated by rotating movement of a switch shaft 43, connected to the control switch and extending substantially from end to end of the tracks parallel thereto, and operated by the operating levers 45 each projecting at opposite sides of the shaft and provided with pendant flexible operating means 46.

The operation of the apparatus is very simple. When there is an article to be con- 110

veyed one of the operating means 46 is pulled causing the motor to rotate in one direction or the other until the trolley is brought over or near the object to be conveyed, whereupon by means of the means 46 the switch of the cable-drive motor is put to neutral position. One of the flexible cables 18 is then inserted in the socket 6 most conveniently located relative to the 10 position of the trolley. Then one of the flexible control devices 21 is pulled, thus supplying current to the hoisting motor to lower the hoisting cable until it is low enough to be attached to the object to be 15 conveyed. The opposed trolley device 21 is then pulled, supplying current to the motor for winding up the cable and raising the object, whereupon the switch of the hoisting motor is put to the neutral position by the 20 operation of the trolley devices 21. Then the cable plug 19 is withdrawn from the socket 6 and attached to a hook or the like upon the trolley, as shown at the left of Fig. 1. One of the flexible operating means 25 46 is then pulled supplying current to the cable motor 35 for moving the trolley and the conveyed object to the desired location. When this desired location is reached, the plug 19 is again inserted into the most 30 conveniently located socket 6 and one of the trolley devices 21 operated to supply current to the hoisting motor for lowering the conveyed object at the required location.

I claim as my invention:

35 1. In combination, overhead trolley tracks; a trolley thereon; a drive means mounted at one end of said tracks and adapted to drive said trolley and provided with a switch shaft extending substantially from 40 end to end of said tracks parallel thereto; and operating levers fixed at intervals along said switch shaft and provided with pendant flexible operating means.

45 2. In combination, a row of sockets; overhead tracks near such sockets; a trolley on said tracks provided with an electric motor and hoisting drum; control devices pending from each motor; an electric conducting cable connected to said motor and provided 50 with a plug adapted to fit any of said sockets; a cable drum and pulley respectively at opposite ends of said tracks; a cable passing over said cable drum and pulley and connected to said trolley; a cable motor for said cable drum; and a control shaft for said motor and extending along 55 said track and provided at intervals with pendant operating means.

60 3. In combination, overhead tracks; a trolley on said tracks provided with hoisting means and a motor therefor; means for supplying current to said motor; a cable drum mounted at the end of said tracks; an idler pulley at the other end of the tracks; a cable 65 connected to said trolley and passed around

said cable drum and pulley; a cable-drive motor geared to said cable drum and provided with a control switch; a switch shaft connected to said control switch and extending substantially from end to end of said 70 tracks parallel thereto; and operating levers fixed at intervals along said switch shaft and provided with pendant flexible operating means.

4. In combination, a row of electric 75 sockets; overhead tracks near such sockets; a trolley on said tracks provided with an electric motor and hoisting drum; control devices pending from each motor; an electric conducting cable connected to said 80 motor and provided with a plug adapted to fit any one of said sockets; a cable drum mounted at the end of said tracks; an idler pulley at the other end of the tracks; a cable connected to said trolley and passed around 85 said cable drum and pulley; a cable-drive motor geared to said cable drum and provided with a control switch; a switch shaft connected to said control switch and extending substantially from end to end of said 90 tracks parallel thereto; and operating levers fixed at intervals along said switch shaft and provided with pendant flexible operating means.

5. In combination, an overhead trolley 95 track; a trolley thereon; a stationary motor operatively connected for driving the trolley and having a control switch; and a control shaft for said switch extending along said track for positively operating 100 the switch for opening and closing.

6. In combination, a horizontal trolley track; a trolley thereon; a fixed motor operatively connected for driving the trolley; a control shaft for said motor extending 105 along said track, and operating means disposed along the shaft for operating the latter.

7. In combination, a trolley track; a trolley supported and guided by said track; a stationary motor operatively connected for driving the trolley; a control shaft for controlling said motor extending along said track; and means whereby the control shaft may be rotated. 110

8. In combination, a trolley track; a trolley thereon; a motor connected for driving said trolley; and a control shaft for controlling said motor extending along said track and provided at intervals with pendant operating means for operating the shaft to control the motor. 115

9. In combination, a trolley track; a trolley thereon; a cable drum at one end of said track; a pulley at the opposite end of the track; a cable passing over said drum and pulley and connected to said trolley; a cable motor for said cable drum; and a control shaft for controlling said motor extending along said track and provided at 120 125 130

intervals with pendant operating means for operating the shaft to control the motor.

10. In combination, overhead tracks; a trolley on said tracks provided with a hoisting motor and hoisting drum; control devices pendant therefrom; an electric conducting cable connected therewith provided with a plug at its end; receptacles for said plug distributed at intervals beneath the 10 overhead track; a cable drum and a pulley at opposite ends of said track; a cable passing over said cable drum and pulley and connected to said trolley; a motor for said cable drum; and a control shaft for controlling said motor extending along said track and provided at intervals with pendant operating means for operating the shaft to control the motor.

11. In combination, an overhead track; an 20 overhead trolley thereon having a hoisting drum and an electric motor for the drum; and a pendant conductor for supplying current to said motor; having a plug at its end; a plurality of upstanding obstructing 25 floor machines beneath said track, each having a socket adapted to receive said plug when the trolley is nearest thereto and give current thereto, said structures forming a barrier substantially preventing the disconnecting 30 of the conduction by the moving

against the conductor of objects upon the floor that might break or displace the conductor.

12. In combination, an overhead track; an 35 overhead trolley thereon having a hoisting means and an electric motor for the hoisting means; a plurality of sockets spaced from each other and disposed between said track and floor beneath said track; a pendant conductor for supplying current to said motor, 40 having a plug at its end adapted to receive one of said sockets when the trolley is nearest thereto and give current thereto; and upstanding obstructing structures associated with the respective sockets, on said 45 floor therebeneath for forming a barrier substantially preventing the disconnecting of the conductor by the moving against the conductor of objects supported upon the floor that might break or displace the conductor; said conductor being short enough 50 to be held substantially free of slack which would permit its lower part to dispose itself to one side of the structures near the floor where it could be contacted by said objects. 55
